UNITED STATES PATENT OFFICE.

DAYTON KRUG, OF CANTON, OHIO, ASSIGNOR TO THE GILLIAM MANUFACTURING COMPANY, OF CANTON, OHIO, A CORPORATION OF OHIO.

HARNESS-SADDLE.

1,099,148.

Specification of Letters Patent.

Patented June 2, 1914.

Application filed March 29, 1909. Serial No. 486,582.

To all whom it may concern:

Be it known that I, DAYTON KRUG, a citizen of the United States, residing at Canton, in the county of Stark and State of Ohio, have invented certain new and useful Improvements in Harness-Saddles, of which the following is a specification, reference being had therein to the accompanying drawings.

10 This invention relates to harness saddles or pads.

One object of the invention is to produce a harness saddle of simple, durable and economical construction and neat in appearance.

15 Another object of the invention is to produce a harness saddle having a jockey detachably connected to the housing of the saddle to permit ready access to parts beneath the jockey.

20 Another object of the invention is to produce a harness saddle with a sewed on bottom and having a jockey that is detachably connected to the housing of the saddle, and adapted to be detached or raised at either 25 end to permit the removal or insertion of a terret nut, or the repairing of parts of the saddle beneath the jockey.

Further objects of the invention consist 30 in the combination or combinations of parts hereinafter referred to and described.

Referring to the drawings, Figure 1 is a perspective view of a harness saddle embodying my invention. Fig. 2 is a similar 35 view showing one side of the jockey and other parts of the saddle, detached. Fig. 3 is a top plan view of a portion of a saddle with the jockey removed. Fig. 4 is a fragmentary longitudinal sectional view of the 40 saddle. Figs. 5 and 6 are transverse sectional views on lines 5—5 and 6—6, respectively, of Fig. 4.

In the drawings, 1 indicates, as a whole, a harness saddle chosen for the purpose of 45 illustrating one embodiment of my invention.

1^a indicates the housing of the saddle to the upper surface of which may be secured beads as indicated at 2, 2. Each of the 50 beads 2 lies close to one of the longitudinal side edges of the housing and preferably conforms to the contour of the said adjacent side edge.

The housing 1^a on opposite sides thereof 55 is formed with openings 1^b (only one such

aperture being shown in the drawings) for the purpose of permitting access to the inside of the saddle, particularly when it becomes necessary to remove or insert a terret nut.

3 indicates a saddle tree of any suitable construction. The tree 3 on opposite sides thereof is formed with apertures 3^a, to receive the terret shanks or body portions of the terret nuts, and openings 3^b, which are disposed immediately below or in line with the openings 1^b formed in the housing 1^a.

4 indicates a jockey preferably provided with a liner 4^a and adapted to lie on the upper surface of the housing 1^a and between the beads 2. The opposite longitudinal edges of the jockey 4 preferably conform to the contours of and are fitted snugly to the inner side walls of the beads 2. It will be noted that the opposite inner side 70 walls of the said beads are substantially perpendicular, and that the edges of the jockey lie in close enough engagement with the housing 1^a and beads 2 to give the saddle a very neat and finished appearance.

80 The jockey 4 may be and preferably is secured centrally of or at the top of the saddle to the housing in any suitable and well known manner. The parts of the jockey at either side of the center or top 85 of the saddle lie substantially flat upon the housing and are detachably secured thereto by the terrets 5 and tree bolts or screws 6. The bolts 6 are preferably arranged near the opposite free ends of the jockey.

90 The liner 4^a is preferably stitched to the jockey 4 around its entire edge, except across the opposite ends of the jockey, where the stitches are omitted to permit the upper ends of skirt straps 7, 7 to be inserted between the jockey 4 and liner 4^a.

95 5^a indicate terret nuts arranged on the lower side of the tree 3 and adapted to receive the shanks of the terrets 5. 6^a indicate suitable nuts, also arranged on the lower side of the tree 3, for the bolts 6.

The skirt straps 7, 7, are formed with apertures 7^a to receive the bolts 6 whereby they are suitably secured to the saddle tree.

105 8 indicates the back bands, one at either side of the saddle.

8^a indicate metal straps each arranged to lie between a skirt 7 and the jockey 4. Each of the straps 8^a is formed with openings 8^b to receive the shank of a terret 5

and a bolt 6. 9 indicate rings of any suitable construction each arranged to connect a back band 8 and the adjacent strap 8^a together.

5 In the saddle illustrated in the drawing, the bottom 10 is sewed or stitched directly to the housing 1^a, as indicated at 10' and a suitable binding 11 is stitched to the housing and bottom, to conceal from view the 10 rough and unfinished edges of those parts.

When it is desired for any purpose to remove a terret nut and insert a new one, or to get beneath either side of the jockey for any purpose, the terret 5 and bolt 6 on that 15 side are removed and the side piece of the jockey 4 thereby freed is raised, and the skirt 7 and strap 8^a detached. This operation exposes to view the interior of the saddle. For withdrawing and replacing a terret nut some suitable nut gripping tool may 20 then be inserted through the opening 1^b in the housing and the opening 3^b in tree 3.

It will be understood that by making the jockey readily detachable, access to various 25 parts of the saddle may be easily had. This construction facilitates the repairing of the saddle and substitution of different parts or trimmings such as terrets, skirts and back bands without damaging the housing, bottoms, beads and binding, and also permits 30 the jockey to be replaced and the parts secured together, leaving the saddle with as neat an appearance as it had before the jockey and other parts of the saddle were 35 detached.

Ofttimes the trade is called upon to change the style and form of terrets, back bands or skirts. Heretofore where such changes have 40 been requested in saddles having sewed on bottoms, so far as I am aware, it has been impossible after the saddle left the manufacturer's hands to readily and satisfactorily effect the desired changes. With saddles embodying my invention such alterations 45 may be readily made, the terrets may be readily changed, even though it is necessary to use and insert a different terret nut than was in the saddle when its manufacture was completed. The saddles may even be sold 50 without trimmings and even without terrets and their terret nuts, and the dealer or user may readily place upon the saddle any suitable or desired terret and trimmings.

To those skilled in the art of making articles of the class described, many alterations in construction and widely differing embodiments and applications of my invention will suggest themselves, without departing from the spirit and scope thereof.

60 My disclosures and the description herein

are purely illustrative, and are not intended to be in any sense limiting.

What I claim is:

1. In a harness saddle, the combination of a housing, a bottom stitched thereto, a tree frame arranged between the housing and the bottom and formed with openings to receive the shanks of terrets and to permit the insertion and removal of terret nuts, the said housing being formed with openings to 65 permit access to the openings formed in the tree frame, a jockey, a liner corresponding in shape and size to the shape and size of said jockey, the said jockey and liner being arranged on the top of the housing, terrets 70 which when removed permit the removal of the jockey and liner from the housing, means for securing the said jockey and said liner together along their opposite longitudinal edges, and a skirt secured to said 75 housing.

2. In a harness saddle, the combination of a housing, a bottom permanently stitched thereto, a tree frame arranged between the housing and the bottom, terrets and tree 85 bolts, a jockey provided with a liner and arranged to lie on the housing and detachably secured thereto by the terrets and tree bolts only, the said liner being of the same width and shape as the jockey and stitched thereto 90 along its longitudinal edges, straps for supporting back bands for the saddle, and skirts, the free ends of the said straps and skirts being arranged between the jockey and the liner and secured to the housing by the tree 95 bolts.

3. In a harness saddle, the combination of a housing, a bottom permanently stitched thereto, a tree frame arranged between the housing and the bottom, terrets and tree 100 bolts, a jockey provided with a liner and arranged to lie on the housing and detachably secured thereto by the terrets and tree bolts only, the said liner being of the same width and shape as the jockey and stitched thereto 105 along its longitudinal edges, straps for supporting back bands for the saddle, skirts, the free ends of the said straps and skirts being arranged between the jockey and the liner and secured to the housing by the tree 110 bolts, and separate means for securing the skirts to the housing below the tree bolts and beyond the opposite ends of the jockey.

In testimony whereof I affix my signature 115 in the presence of two witnesses.

DAYTON KRUG.
